Atty:

UNITED STATES PATENT OFFICE.

JOHN F. DUBBER, OF BROOKLYN, NEW YORK.

WRITING-TABLET.

SPECIFICATION forming part of Letters Patent No. 244,205, dated July 12, 1881.

Application filed November 9, 1880. (No model.)

To all whom it may concern:

Be it known that I, JOHN F. DUBBER, a citizen of the United States, residing at Brooklyn, in the county of Kings and State of New York, 5 have invented new and useful Improvements in Writing-Tablets, of which the following is a specification.

This invention relates to improvements in writing-tablets; and it consists in the combination, with the base-plate, of a transverse spring-plate having its ends bent around and attached to the under side of the base, and its longitudinal body portion intermediate its attached ends entirely disconnected from the 10 base and curved or bent in the direction of its length to bear on the sheets of paper, and provided with a thumb-button for elevating the spring-plate.

This invention is illustrated in the accompanying drawings, in which Figure 1 represents a face view. Fig. 2 is a transverse section in the plane $x x$, Fig. 1.

Similar letters indicate corresponding parts. In the drawings, the letter A designates the 20 base-plate of my writing-tablet, which is made of pasteboard or any other suitable material, and which may be covered with a sheet of blotting-paper, or with any other material suitable for forming a convenient support for sheets 25 of paper during the operation of writing thereon. For the purpose of retaining the sheets of paper on the base-plate I use a spring, B, which is fastened to said base-plate at its ends, while its intermediate portion is left unsupported and bent in such a manner that it bears 30 down upon the surface of the base-plate, or upon the paper resting thereon. In the example shown in the drawings the ends of the spring B are made to straddle the edges of the base-plate, and they are held in position partly by the 35 covering of the spring and partly by the back lining of the base-plate, and I consider this mode of securing said spring to the base-plate very convenient; but it will be readily understood that the ends of the springs may be 40 fastened to the base-plate in any other suitable manner.

In the middle of the spring B is secured a 45 button, C, by means of which said spring can be readily raised for the purpose of introducing beneath it one or more sheets of paper, or for releasing the sheet or sheets previously introduced. At the same time my spring allows of moving the sheets of paper upward on the 55 base-plate during the operation of writing,

so that the hand of the writer has a convenient support down to the bottom line of each sheet.

By the employment of a plate-spring, bent or curved and attached to the base-plate at 60 its ends, as herein described, and provided with the central thumb-button for manipulating the same, I provide an exceedingly simple and comparatively inexpensive writing-tablet, and one in which the back of the tablet is 65 smooth and plain, and can rest in a flat position on a desk or other support.

I am aware that a tablet has been constructed in which a tube has been arranged across the sheets of paper, said tube containing a rubber 70 or a spiral spring, to the outer ends of which spring are connected inelastic cords or tapes, which are attached to the cover or back of the tablet, or to a spring within a tube on the opposite side of the tablet when two tubes are 75 employed. In such construction the cords or tapes are very liable to breakage, and, further, the complicated nature of such device renders it liable to become disarranged or inoperative, owing to the connection of several 80 distinct parts, and the fact that a rubber or spiral spring of the simple character required for the tube will soon lose its inherent elasticity.

I am aware that a clasp for bill-files has 85 been made of a strip of spring metal doubled on itself for encircling the bills, and provided at its adjoining ends with a spring lock or catch, whereby the clasp can be readily detached; but such is not my invention, and is 90 hereby disclaimed.

What I claim as new, and desire to secure by Letters Patent, is—

The combination, with the base-plate of a writing-tablet, of a transverse spring-plate 95 having its ends bent around and attached to the under side of the base, and its longitudinal body portion intermediate its attached ends entirely disconnected from the base and curved or bent in the direction of its length to 100 bear on the sheets of paper, and provided at its center with a thumb-button for elevating the spring-plate, substantially as shown and described.

In testimony whereof I have hereunto set 105 my hand and seal in the presence of two subscribing witnesses.
